 4 Claims. (Cl. 242—130.2)

ABSTRACT OF THE DISCLOSURE

A bobbin holder for fastening yarn bobbins to a bobbin creel, comprising two movable plates for bobbin clamping, exiting from side slots in the bobbin holder, a centering ring and an adjustable braking device, characterized in that the movable plates are of a different length and pivoted to each other at the upper end thereof; the upper end of said longer plate being provided with two opposite projecting parts or elements, adapted to be alternatively engaged by an inner rib of the centering ring during the fastening operation of the bobbin, there being also provided a braking device directly adjustable from outside.

This invention relates to a bobbin holder of an essentially cylindrical shape, formed of two hollow shaft halves within which the rolling bearing, the spring brake and two locking elements are accommodated, the upper and lower ends of said locking elements projecting from longitudinal slots formed along the cylindrical body of the bobbin holder. The lower ends of the two locking elements are for carrying the bobbin body, whereas the upper ends are for engagement by a centering ring sliding along the cylindrical body of the bobbin holder and for being carried to a position wherein said locking elements are ready for duty and from which they tend to pass to an operative position owing to the weight thereof.

The late embodiments of bobbin holders have locking elements formed of two identical plates located against one another and pivoted to one another which, on falling, grip the bobbins within the inner shoulder thereof.

Since the two plates are identical, such embodiments have as a drawback the necessity of providing wide longitudinal slots along the body of the bobbin holder so that the ends of said locking elements be permitted to slide along said slots.

As a result, cotton dust penetrates the bobbin holder very easily and thus after some period of time the movements of the bearing and plates are inhibited.

Generally, bobbin holders are provided with plates with simple clamping foot. In this case, bobbin holders of a different length are to be used depending upon whether the bobbins have a short or a long inner neck; otherwise, should only bobbin holders for long neck bobbins be used, short neck bobbins would hang down into the bobbin creel to a too great extent.

Bobbin holders provided with an inner spring brake have already been carried out, but for these forms it is still necessary to take away the bobbin holder in order that the brake spring force be changed.

The object of the present invention is to provide a bobbin holder avoiding the above described drawbacks and capable at the same time of being manufactured in large amounts from low cost material and thus with a great economical advantage.

Such a problem is solved as follows:

Instead of two identical plates, provision is made for two different interconnected plates, one of which being shorter than the other and without the upper end contact-

2

ing the centering ring. These plates are interconnected at an accurately determined position allowing the smaller plate to be drawn by the larger plate, so as to render more reliable and rapid the balanced movements of the latter. Thus, the smaller plate is caused to follow in an opposite direction the balancing movements of the larger plate due to its guide within the other body half of the bobbin holder.

At the same time, the smaller plate operates to promote the balancing movements and to stabilize the various positions.

Another object of the present invention is to provide for the adjustment of the inner brake by means of an adjustable screw without any need for taking away the bobbin holder.

A third object is to provide plates, in which the feet or lower ends are in the form of steps. Thus, said bobbin holder can grip the long or short inner neck bobbins, without short neck bobbins hanging down for this into the bobbin creel to a too great extent and causing a loss of positions.

Further details of the bobbin holder according to the present invention will be apparent from the following description, reference being made to the accompanying drawings wherein an embodiment is shown, and more particularly:

FIGURE 1 is a side view of the bobbin holder;
 FIGURE 2 is a sectional view according to line II—II in FIGURE 1 of the bobbin holder showing the bobbin at clamped position; wherein the clamping element in dotted lines has been added for greater clarity;

FIGURE 3 is a fragmentary sectional view of the bobbin holder, wherein the clamping elements are shown at retracted position and the clamping element in dotted lines has been added for greater clarity;

FIGURE 4 is a sectional view according to line IV—IV of FIGURE 1; and

FIGURE 5 is a sectional view according to line V—V of FIGURE 1.

Shaft 1 is so suspended as to be pivoted around a screw 3 the end of which penetrates chamber 2 from the top and being surrounded within said chamber by braking members and by the other end connected to the bobbin creel of the machine. Shaft 1 is formed of two separate halves, which are held together by annular springs 21 and 22.

The two plates 5 and 6 (at clamped bobbin position in FIG. 2), pivoted to each other at 10, can upwardly or downwardly slide, drawn by ring 20 engaging the projecting portion 7 of the upper end of plate 6 with rib 24. The movement of plates 5 and 6 is guided by feet 11 and projecting portion 7, slideable within the respective slots 4'', 4'' and 4'. Slots 4' and 4'' are on the same plane (FIGS. 4 and 5), whereas slot 4''' is arranged on a plane parallel to the plane of the other slots (FIGURE 5).

On approaching the end of upward stroke, foot 11 of plate 6, guided by finger or pin 9, re-enters and with its portion 27 over-rides pin 9, as shown in FIGURE 3. At this position, the two plates 5 and 6 are restrained at position of FIGURE 3 and the bobbin can be withdrawn.

At the same time, the portion indicated at 8 exits from slot 4, which is on the same plane as slots 4' and 4''.

By a further upward drawing movement through ring 20, portion 8 of plate 6 will pivot on rib 24, the plates will be removed from the internal position thereof and sidewise outwardly inclined due to weight thereof. On downward guided movement, the plates will as far as possible move their feet away, which feet are guided by pins 9 and 9', respectively, pin 9' (not shown in the figure) being located on the other half of shaft 1. The two plates

are interconnected at 10, so that one plate will draw the other. Since one plate is shorter than the other and the shortest plate is drawn by the longest one, only the upper end of the longest plate will project from slots 4 or 4' to provide the attachment points for the drawing movement by ring 20. As a result, the width of the slots is reduced to a half, as each slot is contemplated for the width of only one clamping plate.

The feet 11 of plates 5 and 6 are in the form of steps and grip the short neck bobbins at the upper-most location indicated at 25 and the long neck bobbins at the lowermost location indicated at 26, this in order to gain space in the bobbin creel.

The bearing and brake system is arranged within chamber 2 and comprises ball bearing 23, brake disc 12, support spring 13 and brake spring 14.

The assembly is secured to the bobbin creel 15 by a hollow screw 3 engaging the support spring 13 by the head thereof.

Inside this hollow screw 3 there is a further screw 16 coaxial thereto, at the bottom having a thread 18 engaging the corresponding threaded inner portion of the hollow screw 3. With the lower portion thereof the brake spring 14 engages the head of screw 16 and with the upper portion thereof the brake disc 12. Screw 16 is caused to advance or to retract by turning the same through nut 17; thus, brake spring 14 can be more or less compressed. Support spring 13 will be more or less compressed depending on weight of bobbin: as a result, spacing between brake disc 12 and screw head 16 will vary and compression of brake spring 14 will vary accordingly. Compression of brake spring 14 can be brought back to an exact value by adjusting screw 16.

At the same time, braking will hence be accomplished, still in connection with the bobbin weight.

In order that the brake of a set of bobbin holders be adjusted to the same value, a scale having graduation marks 19 has been indicated at the upper end of screw 16, so that, depending on compression of spring 14 said marks 19 will project to a larger or lower extent from the upper end of hollow screw 3. Thus, said upper end will act as a pointer for the adjusting scale of the brake. It is thus possible to adjust rapidly and at the same value

an entire set of bobbin holders without having to take them away.

What is claimed is:

1. A bobbin holder for fastening yarn bobbins to a bobbin creel, comprising two movable plates for bobbin clamping, exiting from side slots in the bobbin holder, a centering ring and an adjustable braking device, characterized in that the movable plates are of a different length and pivoted to each other at the upper end thereof; the upper end of said longer plate being provided with two opposite projecting parts or elements, adapted to be alternatively engaged by an inner rib of the centering ring during the fastening operation of the bobbin, said braking device being directly adjustable from outside.
2. A bobbin holder according to claim 1, characterized in that the feet of the movable clamping plates are in the form of steps, and a respective pin located at the bottom of the bobbin holder for guiding said feet during movement.
3. A bobbin holder according to claim 1, characterized in that said braking device is adjustable from outside and comprises a first hollow screw secured to the bobbin creel, a second coaxial screw movable within the former, which screws exit at the top of the bobbin holder, a braking spring bearing with its lower end on the head of said second screw and with the upper end on a braking disc; said second screw having graduation marks at the outer end thereof for adjusting the tension of the braking spring.
4. A bobbin holder according to claim 3, characterized in that in order to adjust the braking effect said second screw has a threaded section at the lower end thereof, screwing on a corresponding threaded section at the lower inner portion of said first hollow screw, so that on turning said second screw the compression of the braking spring can be varied.
